UNITED STATES PATENT OFFICE

MORRIS P. HOLMES, OF CLAREMONT, NEW HAMPSHIRE, ASSIGNOR TO SULLIVAN MACHINERY COMPANY, A CORPORATION OF MASSACHUSETTS

MINING APPARATUS

Application filed September 30, 1926, Serial No. 138,660. Renewed April 23, 1930.

This invention relates to mining apparatus and more particularly to mining machines of the shear or vertical cutter type adapted to operate from the mine trackway.

5 An object of this invention is to provide a mining machine of the wheel mounted type wherein the machine is adapted to insert a shear or vertical cut in the coal face while guided on the mine trackways. Still another 10 object of this invention is to provide an improved shearing machine having a pivoted cutter bar and improved and simplified mechanism for swinging the cutter bar about its pivot. A still further object of this invention is to provide an improved mining 15 machine having improved mechanism associated with the bar swinging mechanism for driving the wheels of the truck. These and other objects of my invention will, however, 20 hereinafter more fully appear.

In the accompanying drawings I have shown for purposes of illustration one form which my invention may assume in practice.

In these drawings,

25 Fig. 1 is a side elevational view of the improved mining apparatus, the cutter bar being shown in a plurality of positions as indicated by dotted lines.

Fig. 2 is a plan view of the apparatus 30 shown in Fig. 1.

Fig. 3 is a transverse horizontal sectional view taken on line 3—3 of Fig. 1.

Fig. 4 is a developed transverse sectional view taken on line 4—4 of Fig. 1.

35 Fig. 5 is a detail view, partially in section, illustrating the operating connections for the truck brake, the view being taken substantially on line 5—5 of Fig. 3.

Fig. 6 is a developed central longitudinally 40 extending horizontal sectional view taken substantially on line 6—6 of Fig. 7 and illustrating the plural speed transmission gearing.

Fig. 7 is a detail transverse vertical sectional view taken substantially on line 7—7 45 of Fig. 6 and looking in the direction of the arrows.

In this illustrative embodiment of my invention I have shown a truck frame 1 mounted on wheels 2 adapted to move relative to

a mine trackway 3 in the usual manner. The truck frame 1 specifically comprises longitudinally extending parallel angle members 4 held in rigid spaced relation by means of transverse plates 5. The angle members 4 carry in a suitable manner the running gear for the truck wheels 2. As shown a generally rectangular elongated machine frame or body 7 is supported on and movable relative to the truck frame 1 in an improved manner to be later described. Further, the machine frame 7 has pivotally mounted thereon an elongated plane cutter bar 8 movable in a vertical plane and about the outer edges of which an endless cutter bit carrying cutter chain 9 is adapted to be circulated, the cutter chain moving in a fixed orbit. The cutter chain 9 is adapted to be driven by means of a usual drive sprocket 10, as clearly shown in Fig. 4. The cutter chain 70 drive sprocket 10 is disposed at the front end of the machine frame 7 and is rotatable about a horizontal axis extending transversely of the machine frame. As shown, the cutter bar 8 is pivoted as at 11 about an axis coincident with the axis of the cutter chain drive sprocket 10 and has secured integral therewith cylindrical bearing members 12 disposed at opposite sides of the sprocket 10, the members 12 respectively engaging bearing surfaces 13 and 14. The sprocket 10 is 75 adapted to be driven from the driving motor, the horizontal longitudinally extending armature shaft of which is clearly shown in Fig. 6 as at 15, through transmission gearing substantially similar to that described in my copending application Ser. No. 619,839, filed Feb. 19, 1923. As the specific driving connections between the motor and the cutter chain drive sprocket do not enter per se 80 into this invention, further detailed description of the same is deemed unnecessary other than to state that the sprocket 10 may be either connected or disconnected from the motor at will.

In specifically describing the improved mechanism for swinging the cutter bar 8 about its pivot 11, it will herein be observed that the rear end of the armature shaft 15 of the driving motor (see Fig. 6) has suitably 100

secured thereto a spur pinion 16 which is adapted to drive the truck wheel driving mechanism and the improved mechanism for swinging the cutter bar about its pivot and including plural speed transmission gearing 5 and controlling clutches, substantially similar to those described in the pending application mentioned above, at a slow speed in one direction or at a fast speed in the opposite direction without reversing the motor. 10 In specifically describing the fast feed transmission mechanism, it will be noted that pinion 16 meshes with a spur gear 17 suitably journaled within bearings 18 carried by the machine frame 7. The gear 17 has secured thereto and rotatable therewith a spur pinion 19 which meshes with a larger internal gear 20. The hub 21 of the gear 20 is herein also journaled on a suitable bearing sleeve 22 on a sleeve clutch member 23 keyed as at 24 to a longitudinally disposed horizontal main driving or transmission shaft 25 journaled at its opposite ends in bearings 26 and 27 suitably carried within the machine frame. 20 Moreover, it will be noted that the clutch member 23 carries a series of friction clutch discs 28 which are interleaved with a corresponding series of clutch discs 29 carried by the sleeve of the internal gear 20. As shown, 25 the sleeve on this internal gear is also provided with a plurality of radially located longitudinally extending slots 30 receiving radial fingers 31 formed on an interlocking member 32 keyed to the hub of the pinion 33 freely rotatable on the shaft 25. Interposed between these fingers 31 are friction clutch operating fingers 34 carried by an axially movable cylindrical plane clutch operating member 35 disposed coaxial with and encircling the hub of the member 32. These fingers 34 extend longitudinally into contact with the adjacent end clutch disc of the clutch 28, 29. As shown, the rear end of the shaft 25 has secured thereto by a key 36 a spur pinion 37 which meshes with a spur gear 38 journaled within suitable bearings 39 carried by the machine frame. The spur gear 38 has secured thereto and rotatable therewith a spur pinion 40 which meshes with a larger internal gear 41 keyed as at 42 to a longitudinally extending horizontal shaft 43 disposed coaxially with the transmission shaft 25. The shaft 43 is journaled in spaced alined bearings 44 and 45 suitably carried by the machine frame. It will thus be evident that rotation of the armature shaft 15 will be transmitted through the pinion 16, gear 17, pinion 19, internal gear 20, friction clutch discs 28, 29, clutch member 23, shaft 25, pinion 37, gear 38, pinion 40, internal gear 41, to the shaft 43 to rotate the latter at a predetermined high or fast speed whenever the clutch controlling member 35 is operated to connect the clutch 28, 29. It will further be noted that this speed may be lowered at will by slipping the friction discs 28, 29 of the clutch. 5 Now referring specifically to the slow speed transmission, it will be noted that when the clutch operating member 35 is in inoperative position and the clutch 28, 29 is released, power will still be transmitted through the interlocking member 32 and the pinion 33 which is freely rotatable on the shaft 25. This pinion 33 in turn meshes with a gear 46 disposed coaxially with the gear 17 and this gear has secured thereto and rotatable therewith a pinion 47 which meshes with a spur gear 48 disposed coaxially with and rotatable on the shaft 25. 10 This gear 48 has secured thereto and rotatable therewith a spur pinion 49 which meshes with a spur gear 50 arranged coaxially with the gear 46 and this gear has secured thereto and rotatable therewith a spur pinion 51. The spur pinion 51 meshes with an internal gear 52 substantially similar to the internal gear 20. The internal gear 52 also houses a friction clutch substantially similar to the clutch heretofore described in connection with the clutch discs 28, 29 and this clutch includes series of interleaved clutch discs 53, 54, certain of which are carried on the clutch member 55 keyed as at 56 to the shaft 25, while others are carried by a sleeve formed on the internal gear 52. A clutch retaining member 57 is provided keyed as at 58 to the hub of the spur pinion 37 and this clutch member in this instance has no interlocking function and is only a disc retaining member. An axially movable cylindrical plane clutch operating member 59 surrounds the hub of the clutch member 57 and is provided with longitudinally extending fingers 60 which are adapted to engage the adjacent end disc of the clutch 53, 54. The clutch operating members 35 and 59 may be operated to alternately apply their respective clutches by means of suitable shifter mechanism which is clearly described in the copending application mentioned above and includes an operating handle 61 conveniently located at the rear end of the machine (see Figs. 1 and 2). As a result of this slow speed mechanism above described, although the clutch 28, 29 is disconnected, rotation will when desired be imparted through the pinion 33, gear 46, pinion 47, gear 48, pinion 49, gear 50, pinion 51, internal gear 52, clutch discs 53, 54, clutch member 55, pinion 37, gear 38, pinion 40, internal gear 41, to the shaft 43 so that when the clutch 53, 54 is connected the shaft 43 will be rotated at a slow speed in an opposite or reverse direction from the fast feed previously described. Here it will also be evident that by slipping the friction discs 53, 54, of the slow speed clutch, this speed may be reduced at will. 15 As shown in Fig. 3, the shaft 43 is made

hollow and has telescopically arranged thereto in a shaft 65, the shaft 65 having external threads 66 engaging internal threads 67 formed within the hollow shaft 43. The shaft 65 has formed thereon longitudinally extending splineways 68 and cooperating with these splineways are splines 70 carried by a slidable member 71 encircling the screw threaded shaft 65 and disposed adjacent the rear end of the hollow shaft 43. As clearly shown in Fig. 3 the member 71 has formed internally thereon gear teeth 72 which are adapted to be connected, by means of a shipper yoke 73 pivotally mounted on the frame 7, to clutch teeth 74 formed externally on the shaft 43. From the foregoing description, it is evident that when the gear teeth 72, 74 are connected, the shaft 43 and the screw threaded shaft 65 may rotate together. However, when the gear teeth 72, 74 are disconnected and when the shaft 65 is suitably held against rotation, the shaft 43 may move inwardly or outwardly relative to the shaft 65 due to the screw threaded connection. As shown, the rear end of the shaft 65 is journaled on ball bearings 75 suitably carried by a housing or casing 76, the latter being rotatably mounted on a separate base frame rigidly secured as by screws 77 to the transverse angle members 4 of the truck frame 1. The shaft 65 has secured thereto at the rear end thereof as by a key 78 a bevel gear 79 which constantly meshes with bevel gears 80 and 81 rotatably mounted on bearing sleeves 82, 83, respectively, surrounding and supported by a horizontal shaft 84 disposed transversely of the truck frame and journaled at its opposite ends in ball bearings 85 suitably carried by the housing 76. The bevel gears 80 and 81 rotate in opposite directions and constitute a reversing mechanism for the shaft 84. As clearly shown in Fig. 3 the adjacent inner sides of the gears 80 and 81 are provided with hub portions 86 having formed thereon spur gear teeth 87 and 88 respectively. The gear teeth 87 and 88 are adapted to be alternatively connected by means of an internal shipper gear 89 to gear teeth 90 preferably formed integral with the shaft 84 intermediate its ends. Cooperating with the internal shipper gear 89 is a shipper yoke 91 suitably secured to a vertically disposed shaft 92 suitably rotatably mounted within the housing 76. The shaft 92 has secured thereto at its upper end an operating lever 93 (see Figs. 1 and 2). It will thus be evident that when the operator suitably swings the lever 93 about its pivot the shipper yoke 91 is consequently swung and the desired gear 87, 88 is connected to the gear 90, thereby connecting one or the other of the bevel gears 80 and 81 in operative driving relation with the shaft 84. The shaft 84 may also be rotated at either a fast or at a slow speed

under the control of the clutches 28, 29 and 53, 54 described above operated by the operating handle 61.

In this instance the shaft 84 has suitably secured thereto at one end thereof a drive sprocket 94 which is connected by means of an endless drive chain 95 with a sprocket 96 suitably secured to the rear truck axle 97. The rear truck axle 97 and the front truck axle 98 are connected in driving relation by a suitable chain and sprocket connection 99. Also secured to the shaft 84 adjacent the drive sprocket 94 as by a key 100 is a brake drum 101 having formed thereon on its external periphery a groove 102 with which a brake band 103 cooperates. The brake band 103 is secured intermediate its ends as at 104 to the housing 76. The brake band may be contracted or expanded by means of suitable toggle mechanism 105 connected through a link 106 to an operating crank 107 pivoted as at 108 on one of the angle members 4 of the truck frame. The lever 107 may be held in its different adjusted positions by means of a suitable spring pressed plunger 109 carried by the lever and cooperating with locking apertures 110 formed in the adjacent angle member 4. This braking device is adapted to control rotation of the truck wheels while the mining apparatus is moving over an inclined trackway and to control rotation of the shaft 84 during operation of the machine during cutting as hereinafter described.

As clearly shown in Figs. 1 and 4, the cutter bar 8 has secured thereto at opposite sides thereof as by rivets 111, angle members 112 and 113 respectively connected as by bolts 114 to parallel supporting arms 115 and 116, the latter being pivotally mounted on bearing sleeves 117 surrounding and supported by the front truck axle 98. These arms 115 and 116 support the forward end of the machine frame 7 and each has a bearing portion 118 carrying a bearing sleeve 119 in which hub portions 120 formed on opposite sides of the machine frame 7 are disposed, the bearing portions 120 being arranged coaxially with the axis of bar swing. From the foregoing description it will be evident that when the shaft 65 is connected by means of the clutch member 73 to the shaft 43 and when one or the other of the gears 87, 88 is connected to the shaft 84, the truck wheels may be driven in opposite directions and at different speeds. It will further be evident that when the gears 74, 72 are disconnected and when the brake band 103 is applied preventing rotation of the screw threaded shaft 65, it being understood that one or the other of the bevel gears 80 and 81 are connected to the shaft 84, the shaft 43 and consequently the machine frame 7 may be moved longitudinally relative to the shaft 65 in either direction and at different speeds. Upon movement of the machine frame 7 the arms 115, 116 swing about the

front truck axle 98 as a pivot and consequently swing the cutter bar about its pivotal axis. During this swinging movement the shaft 65 is adapted to swing or rock slightly about the axis of the shaft 84 and to permit this swinging movement the housing 76 is made separate from its base and is pivotally mounted within bearing sleeves 121 at its opposite sides. The rear end of the machine frame 7 is supported by this housing 76.

In the operation of my improved mining apparatus, it will be noted that when the latter is moving rapidly about the mine the clutch member 71 is moved to connect the gear teeth 72 and 74 and the gear 80 is connected to the shaft 84 by means of the clutch member 89, it being understood that the motor is running and the fast speed clutch 28, 29 is applied, and consequently the shaft 43 and the shaft 65 are rotating at a high speed. When it is desired to drive the mining apparatus rearwardly relative to the trackway at a high speed, the bevel gear 80 is released from the shaft 84 and the bevel gear 81 is connected to the shaft by means of the controlling clutch 89. When the apparatus is disposed adjacent the coal face, the operator disconnects the gear 74 from the gear 72. The brake band 103 is then applied consequently preventing rotation of the shaft 65. Upon continued rotation of the screw threaded shaft 43 at a high speed the same moves rearwardly axially relative to the screw 65 and consequently the machine moves rearwardly relative to the truck frame, the arms 115 and 116 swinging about the front truck axle 98 and consequently swinging the cutter bar 8 upwardly about its pivot 11 at a high speed from the full line position to the upper dotted line position shown in Fig. 1. The operator then suitably connects the cutter chain drive sprocket 10 to the motor and the cutter chain 9 is rapidly circulated about the outer edge of the cutter bar 8 in the usual manner. The fast speed clutch 28, 29 is then released. The operator then connects the gears 72, 74, the clutch member 89 is shifted connecting the bevel gear 81 to the shaft 84, the brake 102, 103 is released, and upon application of the slow speed clutch 53, 54 the cutter bar is sumped into the coal at a cutting speed, the mining apparatus moving bodily along the trackway at that time. After the sumping cut is completed the gears 74, 72 are disconnected and the brake band 103 is again applied, preventing rotation of the shaft 65 and the truck wheels and consequently the cutter bar is swung about its pivot to the lower dotted line position shown in Fig. 1. The gears 72, 74 are then connected, the brake 103 is released, and the bevel gear 80 is connected to the shaft 84 and consequently the cutter bar is retracted from the face at a cutting speed, the mining apparatus moving bodily rearwardly along the track-

way at this time. After the withdrawal cut is completed, the brake is applied, the gears 72, 74 are disconnected and the fast speed clutch 28, 29 is again applied, rotating the shaft 43 at a high speed and consequently moving the machine rapidly rearwardly relative to the truck frame and swinging the bar upwardly about its pivot to the full line position shown in Fig. 1. The gears 72, 74 are then connected, the gear 81 is then connected to the shaft 84 and the mining apparatus is moved rapidly rearwardly along the trackway and from the face. These and other operations and advantages of my improved mining apparatus will be clearly apparent to those skilled in this art.

While I have in this application specifically described one form which my invention may assume in practice, it will be understood that this form of the same has been shown for purposes of illustration and that the invention may be modified and embodied in various other forms without departing from its spirit or the scope of the appended claims.

What I claim as new and desire to secure by Letters Patent is:

1. In a mining apparatus, a wheeled truck frame, a cutter carrying frame supported thereon and movable relative thereto, kerf cutting mechanism including a pivoted cutter bar mounted on said frame and having a relatively fixed pivotal connection with said truck frame, and mechanism for moving said second frame relative to said truck frame to effect swinging movement of said cutter bar about its pivot relatively thereto.

2. In a mining apparatus, a wheeled truck frame, a frame supported thereon and movable longitudinally relative thereto, kerf cutting mechanism including a pivoted cutter bar mounted on said second frame and having a relatively fixed pivotal connection with said truck frame, and mechanism for moving said second frame longitudinally relative to said truck frame to effect swinging movement of said cutter bar about its pivot relatively thereto.

3. In a mining apparatus, a wheeled truck frame, a frame supported thereon and movable relative thereto, kerf cutting mechanism including a pivoted cutter bar mounted on said second frame and having a relatively fixed pivotal connection with said truck frame, a driving motor carried by said second frame, and mechanism driven by said motor for moving said second frame relative to said truck frame to effect swinging movement of said cutter bar about its pivot relatively thereto.

4. In a mining apparatus, a wheel truck frame, a frame supported thereon and movable longitudinally relative thereto, kerf cutting mechanism including a pivoted cutter bar mounted on said second frame and having a relatively fixed pivotal connection

with said truck frame, a driving motor carried by said second frame, and mechanism driven by said motor for moving said second frame longitudinally relative to said truck frame to effect swinging movement of said cutter bar about its pivot relatively thereto.

5. In a mining apparatus, a wheel truck frame, a frame mounted thereon and movable relative thereto, kerf cutting mechanism including a pivoted cutter bar mounted on said second frame and carrying an orbitally movable cutter chain and pivotally connected to said truck frame about an axis lying wholly outside of the orbit of said chain, a plural speed transmission mechanism on said second frame, and mechanism driven through said plural speed transmission mechanism and operatively connected to said cutter bar for moving said second frame relative to said 10 truck frame to effect swinging movement of said cutter bar at different speeds about its pivot relatively thereto.

6. In a mining apparatus, a wheel truck frame, a frame mounted thereon and movable longitudinally relative thereto, kerf cutting mechanism including a pivoted cutter bar mounted on said second frame and carrying an orbitally movable cutter chain and pivotally connected to said truck frame about an axis lying wholly outside of the orbit of said chain, a plural speed transmission mechanism on said second frame, and mechanism driven through said plural speed transmission mechanism and operatively connected to said cutter bar for moving said second frame longitudinally relative to said truck frame to effect swinging movement of said cutter bar at different speeds about its pivot relatively thereto.

40 7. In a mining apparatus, a wheeled truck frame, a frame pivotally mounted thereon, kerf cutting mechanism including a cutter bar mounted on said second frame and swingable relative thereto, and mechanism for moving said second frame about its pivotal mounting on said truck frame to effect swinging movement of said cutter bar about its pivot relatively thereto.

8. In a mining apparatus, a wheeled truck frame, a frame mounted thereon and movable relative thereto, kerf cutting mechanism including a pivoted cutter bar mounted on said second frame and carrying an orbitally movable cutter chain and pivotally connected to said truck frame about an axis lying wholly outside of the orbit of said chain, a plural speed transmission mechanism on said second frame, and mechanism driven through said plural speed transmission mechanism and operatively connected to said cutter bar for moving said second frame relative to said truck frame to effect swinging of said cutter bar about its pivot in opposite directions and at different speeds relatively thereto.

45 9. In a mining apparatus, a wheeled truck

frame having front and rear wheel axles, a frame mounted on said truck frame movable relative thereto, kerf cutting mechanism including a pivoted cutter bar mounted on said second frame, and mechanism for moving said second frame relative to said truck frame to effect swinging movement of said cutter bar about its pivot relatively thereto and including pivotal connections between said cutter bar and the front truck axle.

10. In a mining apparatus, a wheeled truck frame having front and rear wheel axles, a frame mounted on said truck frame and movable relative thereto, kerf cutting mechanism including a pivoted cutter bar mounted on said second frame, and mechanism for moving said second frame relative to said truck frame to effect swinging of said cutter bar about its pivot relatively thereto and including pivotal connections between said cutter bar and one of said truck axles.

11. In a mining apparatus, a wheeled truck frame, a frame mounted thereon and movable relative thereto, kerf cutting mechanism including a pivoted cutter bar mounted on said second frame and carrying an orbitally movable cutter chain, and mechanism for moving said second frame relative to said truck frame to effect swinging movement of said cutter bar about its pivot relatively thereto and including a pivotal connection lying wholly outside of the orbit of said cutter chain and between said cutter bar and said truck frame.

12. In a mining apparatus, a wheeled truck frame, a frame mounted thereon and movable relative thereto, kerf cutting mechanism including a pivoted cutter bar mounted on said second frame, and mechanism for moving said second frame relative to said truck frame to effect swinging movement of said cutter bar about its pivot relatively thereto and including telescopically arranged threadedly connected shafts, and means for effecting rotation of said shafts relative to each other to effect movement of said second frame relative to said truck frame.

13. In a mining apparatus, a truck frame having wheel axles, a frame supported on said truck frame and pivotally connected to one of said axles, kerf cutting mechanism including a pivoted cutter bar mounted on said second frame and mechanism for swinging said second frame about said front truck axle and relative to said truck frame to effect swinging of said cutter bar about its pivot relatively thereto.

14. In a mining apparatus, a wheeled truck frame, a frame supported thereon and movable relative thereto, kerf cutting mechanism including a pivoted cutter bar mounted on said second frame and having a rela-

- tively fixed pivotal connection with said truck frame, a driving motor on said second frame, and mechanism driven by said motor for moving said second frame longitudinally in either direction relative to said truck frame to effect swinging movement of said cutter bar about its pivot in opposite directions relatively thereto.
15. In a mining apparatus, a truck frame having wheel axles, a frame supported on said truck frame, supporting means for the forward end of said second frame comprising parallel arms pivotally connected to the front truck axle, kerf cutting mechanism including a pivoted cutter bar mounted on said second frame and to which said parallel arms are secured, and means for swinging said cutter bar about its pivot relative to said second frame including mechanism for swinging said supporting arms about the front truck axle.
16. In a mining apparatus, a truck frame having wheel axles, a frame supported on said truck frame, supporting means for the forward end of said second frame comprising parallel arms pivotally connected to one of said truck axles, kerf cutting mechanism including a pivoted cutter bar mounted on said second frame and to which said parallel arms are secured, and means for swinging said cutter bar about its pivot relative to said second frame including mechanism for swinging said supporting arms about one of said truck axles.
17. In a mining apparatus, a wheeled truck frame, a frame supported thereon and movable relative thereto, kerf cutting mechanism including a pivoted cutter bar mounted on said second frame, and mechanism for moving said second frame relative to said truck frame to effect swinging movement of said cutter bar about its pivot relatively thereto and including telescopically arranged relatively rotatable elements, and means for effecting relative rotation between said elements to effect movement of said second frame relative to said truck frame.
18. In a mining apparatus, a wheeled truck frame, a frame supported thereon and movable relative thereto, kerf cutting mechanism including a pivoted cutter bar mounted on said second frame, and mechanism for moving said second frame relative to said truck frame to effect swinging of said cutter bar about its pivot relatively thereto including telescopically arranged relatively rotatable elements, means for effecting relative rotation between said elements to effect movement of said second frame relative to said front frame, and means for effecting relative rotation between said elements in opposite directions.
19. In a mining apparatus, a wheeled truck frame, a frame supported thereon and movable relative thereto, kerf cutting mechanism including a pivoted cutter bar mounted on said second frame, and mechanism for moving said second frame relative to said truck frame to effect swinging of said cutter bar about its pivot relatively thereto including a pivoted cutter bar mounted on said second frame, and mechanism for moving said second frame relative to said front frame, and means for effecting relative rotation between said elements in opposite directions.
20. In a mining apparatus, a wheeled truck frame, a frame supported thereon, pivotal connections between the opposite ends of said second frame and said truck frame, kerf cutting mechanism including a pivoted cutter bar mounted on said second frame, and mechanism for moving said second frame about its pivotal connections and relative to said truck frame to effect swinging of said cutter bar about its pivot relatively thereto.
21. In a mining apparatus, a wheeled truck frame, a frame supported thereon and movable relative thereto, kerf cutting mechanism including a pivoted cutter bar mounted on said second frame, and mechanism for moving said machine frame in opposite directions relative to said truck frame to effect swinging of said cutter bar about its pivot in opposite directions relatively thereto and including a reversing mechanism carried by said second frame.
22. In a mining apparatus, a wheeled truck frame, a frame supported thereon and movable relative thereto, kerf cutting mechanism including a pivoted cutter bar mounted on said second frame, and mechanism for moving said second frame relative to said truck frame to effect swinging of said cutter bar about its pivot relatively thereto and including relatively rotatable elements and releasable frictional means for holding one of said elements against rotation.
23. In a mining apparatus, a wheeled truck frame, a frame supported thereon and movable relative thereto, kerf cutting mechanism including a pivoted cutter bar mounted on said second frame, and mechanism for moving said second frame relative to said truck frame to effect swinging of said cutter bar about its pivot relatively thereto and including relatively rotatable elements and releasable frictional means for holding one of said elements against rotation, and means for connecting said elements for simultaneous rotation.
24. In a mining apparatus, a wheeled truck frame, a frame supported thereon and movable relative thereto, kerf cutting mechanism including a pivoted cutter bar mounted on said second frame, a driving motor on said second frame, mechanism driven by said motor for moving said second frame relative to said truck frame to effect swinging of said cutter bar about its pivot relatively thereto including a pivoted cutter bar mounted on said second frame, and mechanism for moving said second frame relative to said front frame, and means for effecting relative rotation between said elements in opposite directions.

cutter bar about its pivot relatively thereto, and means driven by said motor for driving the wheels of said truck.

25. In a mining apparatus, a wheeled truck frame, a frame supported thereon and movable relative thereto, kerf cutting mechanism including a pivoted cutter bar mounted on said second frame, a driving motor on said second frame, mechanism driven by said motor for moving said second frame relative to said truck frame to effect swinging of said cutter bar about its pivot relatively thereto, and means driven by said motor for driving the wheels of said truck in opposite directions.

26. In a mining apparatus, a wheeled truck frame, a frame supported thereon and movable relative thereto, kerf cutting mechanism including a pivoted cutter bar mounted on said second frame, a driving motor on said second frame, mechanism driven by said motor for moving said second frame relative to said truck frame to effect swinging of said cutter bar about its pivot relatively thereto, and means driven by said motor for driving the wheels of said truck in opposite directions and at different speeds.

27. In a mining apparatus, a wheeled truck frame, a machine frame supported thereon and movable relative thereto, said machine frame having mounted thereon a pivoted cutter bar having a relatively fixed pivotal connection with said truck frame, means for swinging said cutter bar about its pivot including mechanism for moving said machine frame relative to said truck frame to effect swinging movement of said cutter bar, and mechanism operatively connected to said machine frame moving mechanism for driving the truck wheels.

28. In a mining apparatus, a wheeled truck frame, a machine frame supported thereon and movable longitudinally relative thereto, said machine frame having mounted thereon a pivoted cutter bar having a relatively fixed pivotal connection with said truck frame, means for swinging said cutter bar about its pivot including mechanism for moving said machine frame longitudinally relative to said truck frame to effect swinging movement of said cutter bar, and mechanism operatively connected to said machine frame moving mechanism for driving the truck wheels.

29. In a mining apparatus, a wheeled truck frame, a machine frame supported thereon and movable relative thereto, said machine frame having mounted thereon a pivoted cutter bar having a relatively fixed pivotal connection with said truck frame and a driving motor in said frame, means driven by said motor for swinging said cutter bar about its pivot including mechanism for moving said machine frame relative to said truck frame to effect bar swing, and mechanism driven by said motor for driving the truck wheels.

30. In a mining apparatus, a wheeled truck frame, a machine frame supported thereon and movable longitudinally relative thereto, said machine frame having mounted thereon a pivoted cutter bar having a relatively pivotal connection with said truck frame and a driving motor in said frame, means driven by said motor for swinging said cutter bar about its pivot including mechanism for moving said machine frame longitudinally relative to said truck frame to effect bar swing, and mechanism driven by said motor for driving the truck wheels.

31. In a mining apparatus, a wheeled truck frame, a machine frame supported thereon and movable relative thereto, said machine frame having cutting mechanism thereon including a pivoted cutter bar swingable in a vertical plane and carrying an orbitally movable cutter chain, and means for moving said machine frame relative to said truck frame, to effect swinging movement of said bar about its pivot including a pivotal connection between said bar and truck frame and lying wholly outside of the orbit of said cutter chain.

32. In a mining apparatus, a wheeled truck frame, a machine frame supported thereon and movable relative thereto, said machine frame having cutting mechanism thereon including a pivoted cutter bar swingable in a vertical plane and carrying an orbitally movable cutter chain, and means for moving said machine frame longitudinally relative to said truck frame to effect swinging movement of said bar about its pivot including a pivotal connection between said bar and truck frame and lying wholly outside of the orbit of said cutter chain.

33. In a mining apparatus, a wheeled truck frame, a machine frame supported thereon and movable relative thereto, said machine frame having cutting mechanism thereon including a pivoted cutter bar carrying an orbitally movable cutter chain and a driving motor in said frame, and means driven by said motor for moving said machine frame relative to said truck frame to effect swinging movement of said bar about its pivot including a pivotal connection between said bar and said truck frame and lying wholly outside of the orbit of said cutter chain.

34. In a mining apparatus, a wheeled truck frame, a machine frame supported thereon and movable relative thereto, said machine frame having cutting mechanism thereon including a pivoted cutter bar carrying an orbitally movable cutter chain and a driving motor in said frame, and means driven by said motor for moving said machine frame longitudinally relative to said truck frame to effect swinging movement of said bar about its pivot including a pivotal connection between said bar and said truck frame and lying

wholly outside of the orbit of said cutter chain.

35. In a mining apparatus, a portable base frame, cutting mechanism thereon including a swingable elongated plane cutter bar, a pivotal connection between the inner end of said bar and said base frame, said bar being pivotally mounted on said base frame, and means pivotally connected to said bar at a point between its outer end and said pivotal connection for swinging said bar relative to said base frame to effect a swinging cut.

36. In a mining apparatus, a portable base frame, cutting mechanism thereon including a swingable cutter bar carrying an orbitally movable cutter chain, a pivotal connection between said bar and said base frame, and means pivotally connected to said bar about an axis lying within the orbit of said cutter chain between the outer end of said bar and said pivotal connection for swinging said bar relative to said base frame to effect a swinging cut.

37. In a mining apparatus, a portable base frame, cutting mechanism thereon including a swingable cutter bar carrying an orbitally movable cutter chain, said cutter bar being pivotally mounted on said base frame about an axis lying wholly outside of the orbit of said chain, and means pivotally connected to said bar about an axis lying within the orbit of said chain for swinging said bar about its pivot relative to said base frame to effect a swinging cut.

38. In a mining apparatus, a portable base frame, cutting mechanism thereon including a swingable cutter bar carrying an orbitally movable cutter chain and having a rigidly connected projecting supporting arm extending outside of the chain orbit, a pivotal connection between the inner end of said supporting arm and said base frame on a horizontal axis lying outside the chain orbit, and means carried by said base frame and operatively connected to said cutter bar to swing the latter about its pivot relative to said base frame to effect a swinging cut.

39. In a mining apparatus, a portable base frame, cutting mechanism mounted thereon including a swingable cutter bar carrying an orbitally movable cutter chain and pivotally mounted on said base frame about a horizontal axis lying wholly outside of the orbit of said cutter chain, and means carried by said base frame and operatively connected to said cutter bar to swing said bar about its pivot relative to said base frame to effect a swinging cut.

40. In a mining apparatus, a portable base frame, a frame mounted thereon and movable relative thereto, cutting mechanism including a swingable cutter bar pivotally connected to said frames at relatively fixed spaced points respectively, and mechanism for moving said second mentioned frame relative to

said base frame to swing said cutter bar relative to said frames to effect a swinging cut.

41. In a mining apparatus, a portable base frame, cutting mechanism thereon including a pivoted cutter bar and a pivotal mounting for said bar whose pivotal axis is parallel to but offset from the bar pivot axis, a pivotal connection between said bar mounting and said base frame on a third axis, and mechanism for effecting swinging movement of said bar mounting relative to said base frame to swing said bar relative to said frame to effect a swinging cut.

42. In a mining apparatus, a portable base frame, cutting mechanism thereon including a pivoted cutter bar and a pivotal mounting for said bar, said cutter bar being pivotally connected to said mounting and to said base frame, and mechanism for effecting movement of said bar mounting relative to said base frame to swing said bar relative to said base frame and said mounting to effect a swinging cut.

43. In a mining apparatus, a portable base frame, cutting mechanism thereon including a pivoted cutter bar and a pivotal mounting for said bar, a member secured to and supporting said bar and pivotally connected to said base frame, and means for swinging said bar mounting relative to said base frame to swing said bar relative to said base frame and said mounting to effect a swinging cut.

44. In a mining apparatus, a portable base frame, cutting mechanism thereon including a pivoted cutter bar, a pivotal mounting for said bar, an arm extending radially from the pivotal axis of said bar on said mounting and secured at its outer end to said bar, a pivotal connection between the inner end of said arm and said base frame, and means for moving said bar mounting for swinging said arm relative to said base frame to swing said cutter bar relative to said base frame and said mounting to effect a swinging cut.

45. In a mining apparatus, a portable base frame, a frame supported thereon and movable relative thereto, kerf cutting mechanism including a pivoted cutter bar mounted on said second frame and having a relatively fixed pivotal connection with said base frame, and mechanism for moving said second frame relative to said base frame to effect swinging movement of said cutter bar about its pivot relatively thereto.

46. In a mining apparatus, a portable base frame, a frame mounted thereon and movable relative thereto, kerf cutting mechanism including a pivoted cutter bar mounted on said second frame and carrying an orbitally movable cutter chain, and mechanism for moving said second frame relative to said base frame to effect swinging movement of said cutter bar about its pivot relatively thereto and including a pivotal connection lying wholly outside the orbit of said cutter

chain and between said cutter bar and said base frame.

47. In a mining apparatus, a wheeled truck adapted to run along a mine trackway, a frame mounted on said truck for movement longitudinally relative thereto, kerf cutting mechanism carried by said frame and including a pivoted kerf cutter, a pivotal mounting for said kerf cutter connected between said frame and truck, a motor carried by said frame for driving said kerf cutting mechanism, devices driven by said motor for moving said frame longitudinally relative to said truck to effect swinging movement of said kerf cutter about its pivot relatively thereto, and devices driven by said motor for driving the truck wheels irrespective of the position of said second frame relative to said truck.

48. In a mining apparatus, a wheeled truck adapted to run along a mine trackway, a frame mounted on said truck for movement longitudinally relative thereto, kerf cutting mechanism carried by said frame and including a pivoted kerf cutter swingable in a vertical plane to cut a vertical kerf, a pivotal mounting for said kerf cutter connected between said frame and truck, a motor carried by said frame for driving said kerf cutting mechanism, devices driven by said motor for moving said frame longitudinally relative to said truck to effect swinging movement of said kerf cutter about its pivot relatively thereto, and devices driven by said motor for driving the truck wheels irrespective of the position of said second frame relative to said truck.

49. In a mining apparatus, a wheeled truck frame, a machine body supported thereon and movable longitudinally relative thereto, said machine body having mounted thereon a pivoted cutter bar carrying an orbitally movable cutter chain, and means for swinging said cutter bar about its pivot including mechanism for moving said machine body longitudinally relative to said truck frame, and connections between said cutter bar and said truck frame and lying wholly outside of said cutter chain orbit.

50. In a mining apparatus, a wheeled truck frame, a machine body supported thereon and movable longitudinally relative thereto, said machine body having mounted thereon a pivoted cutter bar carrying an orbitally movable cutter chain and a driving motor in said body, and means driven by said motor for swinging said cutter bar about its pivot including mechanism for moving said machine body longitudinally relative to said truck frame, and connections between said cutter bar and said truck frame and lying wholly outside the orbit of said cutter chain.

51. In a mining apparatus, a wheeled truck frame, a machine body mounted thereon and movable longitudinally relative thereto, said

machine body having mounted thereon a pivoted cutter bar carrying an orbitally movable cutter chain, and means for swinging said cutter bar about its pivot to positions wherein the cutting portion thereof lies at opposite sides of a longitudinal plane including the cutter bar pivot and including connections between said cutter bar and said truck frame and lying wholly outside of said cutter chain orbit.

52. In a mining apparatus, a wheeled truck frame, a machine body supported thereon and movable longitudinally relative thereto, said machine body having mounted thereon a pivoted cutter bar, means for swinging said cutter bar about its pivot, and means for driving the wheels of said truck, said bar swinging means and said truck driving means being only alternatively operable.

In testimony whereof I affix my signature. 85
MORRIS P. HOLMES.
